FIG. 1 is a top plan view of a mount for installing an optical sighting aid on a rifle showing my new design;

FIG. 2 is a right side elevation view, with the left side elevation view being a mirror image thereof;

FIG. 3 is a bottom plan view thereof;

FIG. 4 is a an enlarged front elevation view thereof;

FIG. 5 is an enlarged cross-sectional view, taken by the lines V—V in FIG. 1;

FIG. 6 is an enlarged cross-sectional view, taken by the lines VI—VI thereof;

FIG. 7 is an enlarged cross-sectional view, taken by the lines VII—VII thereof;

FIG. 8 is an enlarged cross-sectional view, taken by the lines VIII—VIII thereof;

FIG. 9 is an enlarged cross-sectional view, taken by the lines IX—IX thereof;

FIG. 10 is an enlarged rear elevational view of FIG. 1;

FIG. 11 is a top and front perspective view thereof;

FIG. 12 is a rear and bottom perspective view thereof; and,

FIG. 13 is a front and bottom perspective view thereof.
